ATTORNEY

UNITED STATES PATENT OFFICE.

ROBERT WENTWORTH FLOYD, OF MONTCLAIR, NEW JERSEY.

PUMP.

Application filed August 5, 1924. Serial No. 730,138.

To all whom it may concern:

Be it known that I, ROBERT WENTWORTH FLOYD, a citizen of the United States, residing at Montclair, in the county of Essex and 5 State of New Jersey, have invented certain new and useful Improvements in Pumps, of which the following is a specification.

This invention relates to a manually operable pump of the plunger type, which is particularly, although not exclusively, useful in connection with hydrostatic jacks. The invention is equally applicable to a pump that takes in and discharges a liquid, and a pulsator that merely moves a column 10 of liquid back and forth. Certain types of such hydrostatic jacks are provided with a pump which is pivotally connected to a pipe or conduit pivotally associated at its other end with the jack proper, an arrangement 15 which has the advantages, among others, that it enables the pump to be operated at some distance from the jack and permits the pump and the conduit to be folded into substantially parallel relationship with the axis 20 of the jack, for convenience of storage.

The pump hereinafter described may be used in place of the pivotally connected pipe and pump used with jacks of the type above mentioned, and offers the same advantages 25 as that arrangement, besides possessing additional advantages among which may be mentioned the avoidance of a pivotal joint and the objections inherent therein.

Generally speaking, the invention is characterized by the fact that the pump casing, 30 the pump cylinder, the piston and the actuating means for the latter are telescopically arranged, thereby permitting the extension of the pump casing so as to facilitate manual 35 operation of the pump at a distance from the jack, for example, when the jack is located under a motor vehicle or at some other place which makes it inconvenient for the operator to work the pump from a position 40 close to the jack.

The invention will be understood from the following description of a preferred embodiment thereof, taken in connection with the accompanying drawings in which Figure 1 is a side elevation of a hydrostatic jack having the invention applied thereto, the pump being in its collapsed position; Figure 2 is a plan view of said jack and pump, with the pump piston drawn out;

Figure 3 is a sectional view of the pump 55 with the parts extended as in Figure 2; Figure 4 is a view similar to Figure 3, but with the pump plunger pushed into the casing preparatory to collapsing the latter; Figure 5 is a sectional view, on an enlarged 60 scale, similar to Figures 3 and 4, but with the pump fully collapsed; Figure 6 is a fragmentary longitudinal sectional view of the shell which serves as a connection 65 between the handle of the pump and the pump piston; and Figure 7 is an end view of the shell shown in Figure 6.

Referring to the drawings, the pump, which is hereinafter described in detail, is shown applied to a hydraulic jack having 70 a casing 10, and a lifting platform 11 which is supported on the outer end of a plunger which moves vertically in the casing 10. The internal construction of said jack forms no part of the present invention and need 75 not be described further than to say that within the casing 10 is a reservoir for the oil or other motive fluid which, in the operation of the jack, is drawn and forced thru suitable valves located within the casing, by 80 the pump hereinafter described. The particular jack illustrated is of a type characterized by the fact that the pump, by which the jack is operated, is pivotally connected to the jack casing as shown at 12, in such a 85 manner that lowering of the jack platform 11 may be effected by moving the pump to a downwardly inclined position with reference to the jack. It will be understood, however, that the pump hereinafter de 90 scribed is not limited to use with a jack of this or any other kind.

The pump which forms the subject of the present invention will now be described. As shown, the various parts of the pump are 95 supported on a base member 15 having a tapered end 16, adapted to cooperate with a tapered hole in the extension 12 of the jack casing. As shown, this base member is L shaped and provided with a passage 18 100 through which the oil or other liquid used in the jack is pumped. Secured to the base member 15 is a telescopic casing which is shown as comprising an outer member 20, permanently secured to the base member 15 in any suitable manner as by brazing, and an inner member 22 which slidingly fits the member 20.

In order to hold the inside casing 22 at either its collapsed or its extended position with reference to the outer casing 20, the inner casing 22 is shown as provided at its inner end with a thick washer 24 secured to inner casing 22 and at opposite points provided with cavities adapted to receive coiled springs 26 and the enlarged heads 27 of locking buttons 28, as clearly shown in Figure 5. When the casing members are completely collapsed, as shown in Figure 5, the outer ends of buttons 28 enter holes 30 in the outer casing member 20, and thus lock the casing members against relative movement. When the inner casing member 22 is extended, as shown in Figure 4, the outer ends of the buttons 28 enter holes 31 in the casing 20, thus locking the casing members in their extended position with reference to one another.

Within the telescopic casing and concentric therewith, is the pump cylinder 34, in the form of a tube, one end of which is threaded and screws into a cavity aligning with the passage 18 in the base member 15. The pump plunger or piston inside the cylinder 34 is shown as composed of rod 35, provided with a disc-shaped head 36. The rod 35 passes through a stuffing box which, as shown, comprises a shell 39, at one end in threaded engagement with the end of the cylinder 34, as shown at 40, and at the other end provided with a lip 42 which surrounds the plunger 35. As shown in Figure 5, the stuffing box contains packing 44 which is constantly compressed by a ring 45 surrounding the piston 35 and forced longitudinally thereof by a coiled spring 46 interposed between the end of the cylinder 34 and said ring 45.

Telescopically arranged in the casing member 22 is a shell 48 which is part of a manually operable means for reciprocating the plunger or piston 35. This shell 48 is shown as provided with a lug 50 adapted to slide in a groove 51 in the inside of the casing member 22, thereby preventing rotary movement of said shell and casing member with reference to one another. At its outer end, the shell 48 is provided with a button or handle 54 which is so secured to said shell as to be rotatable thereon. As shown, this rotatable connection comprises a cap-screw 55 which loosely passes through a disc secured in the outer end of the shell 48, and screws into said handle 54. Handle 54 is provided with a threaded extension 58, adapted to cooperate with threads on the inside of the inner casing member 22, thereby releasably securing the shell 48 within casing member 22 when the former is collapsed with the latter. As shown, the inner casing 22 is a single piece of metal, thicker throughout its right-hand portion than its left-hand portion; but it will be understood that in prac-

tice said member 22 will be made of two tubes, one of which is secured within the other, the inner tube being provided with a slot 51 throughout the major portion of its length.

The shell 48, at its inner end, is provided with means adapted to engage and grasp the head 36 of the plunger 35. As shown, this means comprises a plurality of pairs of lips 60 and 61 which may be formed in the shell 48 in the manner best shown in Figures 5, 6 and 7. Between each pair of lips 60 and 61, the shell 48 is slotted as best shown at 64 in Figures 6 and 7, thereby in effect, dividing the inner end of the shell 48 into fingers. When the telescopic casing members 20 and 22 have been fully extended to the position shown in Figure 4, the aforesaid fingers on the end of the tube 48 by which the lips 60 and 61 are carried, are flexed, as shown in Figure 4, owing to the engagement of all the lips 60 and 61 with the outer surface of the shell 39 of the stuffing box, which acts as a cam. As the shell 48 is pulled outwardly from the position shown in Figure 4, the lips 60 and 61 ride along the surface of the shell 39 until, upon leaving it, they snap into engagement with the head 36 on the end of the pump plunger 35. After this has happened, the shell 48 is positively secured to the end of the plunger 35, as shown in Figure 3, and reciprocation of the shell 48 within the telescopic casing is transmitted to the pump plunger 35. The operator may, therefore, operate the pump by applying one hand to the button 34 and forcing the shell 48 inwardly and outwardly in the pump casing.

After a pumping operation has been completed, the handle 54 and shell 48 may be moved from the position shown in Figure 3 to that shown in Figure 4, after which the buttons 28 may be pushed inwardly enough to release their ends from the holes 31, whereupon the inner casing member 22 may be collapsed into the outer casing member 20, from the position shown in Figure 4 to that shown in Figure 5. If it is found that the buttons 28 do not readily register with the holes 30 and 31 when the telescopic casing is moved from its collapsed to its extended position and vice versa, the casing member 22 may be easily rotated with reference to the casing member 20, by grasping the handle 34 which screws into the casing member 22 and is thus non-rotatable in one direction with reference to the latter. In extending the telescopic casing, the washer 24 engages the inner end of the shell 39 and thus prevents the casing sections from being completely separated.

While I have shown and described what I consider to be a preferred embodiment of my invention, it is of course to be understood that this may be modified in many

respects without departing from the spirit of the invention as defined in the claims hereto appended.

What I claim is:

- 5 1. In a pump, a telescopic casing, a cylinder mounted within said casing, a piston in said cylinder, and means telescopically arranged within said casing and capable of connection with said piston and adapted for 10 manual manipulation to reciprocate the latter when the casing is extended.
2. In a pump, a telescopic casing, a cylinder fixedly mounted within said casing, a piston in said cylinder, manually operable 15 means telescopically arranged within said casing, and means for detachably connecting said piston and said manually operable means, whereby the piston may be reciprocated when the casing is extended.
- 20 3. In a pump, a telescopic casing, a cylinder mounted within said casing, a piston in said cylinder, a shell telescopically arranged within said casing and capable of connection with and disconnection from said piston and adapted for manual manipulation to reciprocate the latter.
- 25 4. In a pump, a telescopic casing, a cylinder mounted within said casing, a piston in said cylinder, a shell telescopically arranged within said casing, and means carried by the inner end of said shell for connecting and disconnecting the latter from said piston, whereby the piston may be reciprocated by manual manipulation of said shell.
- 30 5. In a pump, a telescopic casing, a cylinder mounted within said casing, a piston in said cylinder, a shell telescopically arranged within said casing and adapted to 35 enter the space between said casing and said cylinder when the casing is in its collapsed position, and means for automatically effecting connection and disconnection between said shell and piston when said casing and shell are extended and collapsed respectively.
- 40 6. In a pump, a telescopic casing, a cylinder mounted within said casing, a plunger arranged for movement in said cylinder and having an end ejecting therefrom, a shell telescopically arranged within said casing, and means carried by said shell for auto-

55 matically effecting connection with and disconnection from the end of said plunger when said casing and shell are extended and collapsed respectively.

60 7. In a pump, a telescopic casing, a cylinder mounted within said casing, a piston in said cylinder, a shell telescopically arranged within said casing and nonrotatable with reference thereto, means for effecting 65 connection and disconnection between said piston and said shell when said casing and shell are in their extended and collapsed positions respectively, and means for securing said casing and shell in their collapsed positions.

70 8. In a pump, a telescopic casing, a cylinder mounted within said casing, a piston in said cylinder, a shell telescopically arranged within said casing and nonrotatable with reference thereto, means for effecting 75 connection and disconnection between said piston and said shell when said casing and shell are in their extended and collapsed positions respectively, and a movable handle carried by said shell and adapted to cooperate with said casing for releasably connecting said shell with said casing.

80 9. In a pump, a telescopic casing, a cylinder mounted within said casing, a plunger in said cylinder having an end projecting from the latter, a shell telescopically arranged within said casing, movable means carried by said shell adapted to engage the 85 end of said plunger, and a cam member carried by said cylinder and cooperating with said shell and serving to move the latter into and out of locking engagement with said plunger.

90 10. In a pump, a base member, a telescopic casing secured thereto, a cylinder secured at one end and to said base member within said casing, a piston in said cylinder, and means telescopically arranged 95 within said casing and capable of connection with and disconnection from said piston and adapted for manual manipulation to reciprocate the latter when the casing is extended.

100 In testimony whereof I have affixed my signature to this specification.

ROBERT WENTWORTH FLOYD.
